UNITED STATES PATENT OFFICE.

JOHN H. WELLS, OF BROOKLYN, NEW YORK.

ROCKING-CHAIR.

Specification of Letters Patent No. 26,312, dated November 29, 1859.

To all whom it may concern:

Be it known that I, JOHN H. WELLS, of Brooklyn, in the county of Kings and State of New York, have invented an Improvement in Rocking-Chairs, the construction and operation of which I have described in the following specification and illustrated in its accompanying drawings with sufficient clearness to enable competent and skilful workmen in the arts to which it pertains or is most nearly allied to make and use my invention.

Various modes have been devised for the construction of a chair to allow the vibratory motion of the body without the injurious effect of the action of the rockers upon the carpet, and for the purpose of, at the same time, avoiding other grave objections which attach to the common rocking chair now in general use.

My said invention consists in the arrangement of parts hereinafter described, by which difficulties are obviated, and a favorable disposition of material to resist the strain imposed is secured, thereby reducing the expense of construction, and making a neater, better, and more reliable chair.

The accompanying drawings represent my invention as follows:

30 Figure 1 is a vertical section of my chair as made by a plane passing through the center from front to back. Fig. 2 is a vertical section showing the parts at the right hand side of the line XX, as drawn across Fig.

35 1. The cushions are not shown.

1, 2, 3, and 4, are the legs of the chair, which legs may be connected by any suitable framework, and constitute the lower part of the chair. This frame will of course be varied to suit different tastes, and as various modes are well known, it is not necessary to describe any of them. It will be observed that the legs are differently arranged in this chair from the construction in common use; the legs 1 and 2 being placed at the sides about midway from front to back, and the legs 3 and 4 being placed centrally at the front and back of the seat respectively. The legs 1 and 2 are surmounted by metallic

50 caps 5, of which the tenons 6 form a part. These tenons 6 fit into mortises in the side

rails which support the seat, and are secured in these mortises by pins 7 which pass through the tenons, and form an axis upon which the body of the chair may vibrate, 55 the mortises being made of proper size and form to allow such vibration or rocking motion. To give the body of the chair a normal position, and to regulate the rocking motion, I attach spiral springs 8 and 9 to 60 the front and back respectively of the frame which supports the seat as shown. These springs I extend downward through the legs 3 and 4, nearly to the floor, these legs being made hollow for that purpose. The springs 65 are made fast at both ends to metallic fastenings 10 and 11, so as to cause each spring to resist vibration in either direction. These fastenings are secured to the legs and to the body portions of the chair by any convenient 70 means. The front and back posts are cut away at the top to allow the upper part of the chair to vibrate. They are, however, left a sufficient length to restrict the vibration or rocking motion within proper limits. 75 The outer portions of the front and back rails of the seat frame are extended downward a short distance to cover and conceal the springs. The back rail is raised somewhat in the center, to give greater range to 80 the rocking motion. As above stated, the attachments to which the springs 8 and 9 are secured, may be attached to the body of the seat frame in any desirable manner, but I have deemed it best to attach them by a 85 hinge joint, so as to keep the springs straight or in line. The back post or leg 4 is extended backward to give stability to the chair when rocking back.

The value and utility of a chair which 90 answers the purpose of an easy rocking chair while at the same time it avoids the injurious effect of rockers upon the carpet, and is still cheap and strong in its construction and tasteful in its appearance, is perhaps too 95 obvious to require extended comment; but in order to realize such an advantage the parts must be so arranged as to be strong and reliable without being cumbrous and unwieldy.

Having thus fully described my said invention, I wish it understood that I do not

claim all constructions by which the upper part of a chair may be allowed to vibrate upon the lower, but

I claim as my invention—

5 The arrangement herein described, of the legs 1, 2, 3, 4, the hinge joint at 7, 7, connecting the seat with the underwork, and

the springs 8 and 9, substantially as and for the purpose set forth.

JNO. H. WELLS.
